(57) **CLAIM**

The ornamental design for a multi-functional desk or table lamp, as shown and described.

DESCRIPTION

FIG. 1 is an isometric view of a multi-functional desk or table lamp, embodying our new design;

FIG. 2 is a front view of a multi-functional desk or table lamp, embodying our new design as shown in FIG. 1;

FIG. 3 is a rear view of a multi-functional desk or table lamp, embodying our new design as shown in FIG. 1;

FIG. 4 is a right-side view of a multi-functional desk or table lamp, embodying our new design as shown in FIG. 1;

FIG. 5 is a left side view of a multi-functional desk or table lamp, embodying our new design as shown in FIG. 1;

FIG. 6 is a top plan view of a multi-functional desk or table lamp, embodying our new design as shown in FIG. 1;

FIG. 7 is a bottom view of a multi-functional desk or table lamp, embodying our new design as shown in FIG. 1;

FIG. 8 is an isometric view of a multi-function desk or table lamp, showing the pivoting arm in an alternate vertical state, embodying our new design as shown in FIG. 1;

FIG. 9 is a right-side view of a multi-function desk or table lamp, showing the pivoting arm in an alternate vertical state, embodying our new design as shown in FIG. 1;

FIG. 10 is a left side view of a multi-function desk or table lamp, showing the pivoting arm in an alternate vertical state, embodying our new design as shown in FIG. 1;

FIG. 11 is a front view of a multi-function desk or table lamp, showing the pivoting arm in an alternate vertical state, embodying our new design as shown in FIG. 1;

FIG. 12 is a rear view of a multi-function desk or table lamp, showing the pivoting arm in an alternate vertical state, embodying our new design as shown in FIG. 1;

(Continued)

FIG. 13 is a top side view of a multi-functional desk or table lamp, showing the pivoting arm in an alternate vertical state, embodying our new design as shown in FIG. 1; and, FIG. 14 is a bottom side view of a multi-functional desk or table lamp, showing the pivoting arm in an alternate vertical state, embodying our new design as shown in FIG. 1. The broken lines shown in the drawings are included for the purpose of illustrating portions of the multi-functional desk or table lamp and form no part of the claimed design.

1 Claim, 13 Drawing Sheets
